United States Patent Office

Des. 188,118
Patented June 7, 1960

188,118

DOLL'S HEAD

Ferruccio Bonomi, 38 Via Sardegna, Milan, Italy

Filed Feb. 9, 1960, Ser. No. 59,319

Term of patent 14 years

(Cl. D34—4)

Fig. 2.

Fig. 3.

Fig. 4.

Fig. 1 is a front elevation of a doll head embodying the design invention;

Fig. 2 is a side elevation thereof;

Fig. 3 is a rear view of the same; and

Fig. 4 is another view thereof with a portion of the hair omitted for convenience of illustration.

This application is a continuation in part of prior co-pending application No. D. 57,376, filed August 31, 1959, now abandoned.

I claim:

The ornamental design for a doll's head, as shown and described.
